APPARATUS FOR CONTINUOUS EXTRACTION

George E. Ramer, Wilmington, Del., assignor to
 Hercules Powder Company, Wilmington, Del.,
 a corporation of Delaware

Application March 20, 1934, Serial No. 716,477

6 Claims. (Cl. 202—98)

This invention is directed to a method and apparatus for the continuous extraction of materials; more particularly, for the continuous extraction of resinous wood, as, for example, pine 5 stumps and roots.

The so-called steam and solvent process for the recovery of turpentine, other essential oils and rosin from dead stump wood of the southern pine is well known. This process involves steam- 10 ing the chipped wood with live steam for the distillation therefrom of turpentine and other essential oils, followed, after a thorough drying of the steamed chips, by an extraction thereof with a rosin solvent, usually gasoline. The rosin gasoline 15 solution is subsequently evaporated, either before or after refining treatments, for the production of rosin, and the extracted chips are subjected to a second steam distillation for the recovery of the solvent remaining in them, after which they 20 are usually burned as fuel for the operation of the plant.

The customary and known procedure for carrying out these operations involves chipping the wood in suitable machines and transporting the 25 chipped wood on a belt conveyor to a series of relatively tall extractors which are charged with the chips. In each of these extractors, all the operations described above are performed in sequence. That is to say, the chips are first 30 steamed in the extractor, then dried, extracted with solvent and steamed again for solvent recovery. This utilization of a single extractor unit for all these varied operations involves numerous difficulties, among which may be mentioned the harmful effect on the extractor of operation in rapid succession at different extremes 35 of temperature. After the operations are over, it is necessary to dig out the chips by hand from a door at the side of the extractor.

40 It is obvious that there would be many advantages in operating the steam and solvent extraction as a continuous process rather than as a batch process, as described above. This, however, is impossible with the use of the present 45 forms of apparatus, since, apart from other considerations, the expense of loading and unloading each extractor after only one of the operations had been performed therein would be prohibitive. It is accordingly the purpose of this 50 invention to provide a method and apparatus whereby the steam and solvent extraction of the pine wood may be carried out continuously and without the disadvantages involved in a batch operation.

55 Broadly, the method, in accordance with this

invention, involves the subjection of the chipped pine wood to one operation only, for example, steam distillation of the turpentine in one or more extractors, removal of the chipped wood from this extractor, or group of extractors, into 5 a second group of extractors in which a second operation only will be performed, for example, the dehydration of the chipped wood, and so on throughout the entire cycle of operations necessary for the complete processing of the wood. 10

The apparatus, in accordance with this invention, will accordingly comprise, broadly, a series of extractors, separate groups of which will be designed and adapted for the performance of one operation only in connection with the extraction of the wood, and means for moving the chipped wood in a continuous manner from extractor to extractor throughout the series until it is completely processed.

The practical embodiment of the method in accordance with this invention is most clearly shown by a description of the accompanying drawings, which show a preferred form of apparatus in accordance with this invention, and in which—

25 Fig. 1 is a diagrammatic representation of the complete apparatus in accordance with this invention, comprising extractors, cars for the transportation of chips through the extractors and the pipe lines, condensers, separators, etc. connected and associated with the various extractor units.

30 Fig. 2 is a diagrammatic representation showing the sequence of operation of various valves and controls associated with one complete cycle of extraction.

35 Fig. 3 is a longitudinal section through one of the extractor units and through the car in place in the unit.

40 Fig. 4 is a cross section through one of the extractor units and through the car in place in the unit.

45 Fig. 5 is a cross section through one of the extractor units showing diagrammatically the pipes, valves and electrical controls associated with each extractor unit in its operation.

50 As shown in Fig. 1, the apparatus in accordance with this invention comprises a number of cylindrical extractors (12 are shown in Fig. 1, but any desirable number, either lesser or greater, may be employed) laid horizontally end to end and separated by gate valves VA—1, VA, VB, etc., cars running on tracks extending through these extractors, each car being adapted to closely fit in each extractor unit, and the pipes, 55

pumps, condensers, separators and control valves associated with the extractors.

Each extractor unit comprises (reference now being made to Figs. 3, 4 and 5) a shell 1, which, 5 together with the gate valves 2, forms a closed cylinder. The extractor is adapted to be supplied, through the header 4 and connections 5, with steam, dehydrating vapors, or solvent, as the case may be, depending upon which phase of the 10 operation is to be conducted in this extractor. This steam, dehydrating vapors or solvent may escape from the extractor through pipes 7 and the header 6.

A cylindrical car 8, divided into sections 9 by 15 partitions therein and with its lower and upper surfaces perforated as shown at 10 and hinged at 11 to permit loading and unloading thereof, is carried in the extractor by means of the wheels 11 travelling on the rails 12 which form a part 20 of the extractor. The car may be moved into or out of the extractor by means of the gears 13, which engage with a pinion 14 carried on the bottom of the car. The gears are driven by a main drive shaft 16 through a clutch 15. A vapor 25 seal between the body of the car and the body of the extractor is provided by gaskets 18.

The gate valves 2, which close the ends of the extractor, are operated by the hydraulic cylinders 20, which are provided with a piston 41 and 30 with intake and exhaust lines 21 and 42, respectively. A retarding valve 34 is provided in line 21 to prevent too rapid descent of the piston of the gate valve.

The various operations taking place in each 35 extractor unit are controlled in the following manner:

The headers 4 and 6 are connected with pipe 40 lines 31 and 32, respectively, in which are placed electrically operated valves 27 and 28, respectively, as well as manually operated valves 36 and 35, respectively. The manually operated valves are for emergency use only and are normally 45 always open, the control of the vapors or liquids passing through lines 31 and 32 being performed by the electrically operated valves.

The operation of the gears 13 which serve to move the car is controlled by solenoid 30 operating through lever 37 and the clutch 15. Similarly, the operation of the gate valves 2 is controlled by electrically operated valve 29 placed in the line 21 supplying the cylinder 20. This line has also a manually operated valve 33 for emergency use.

All these electrically operated valves, clutches, 55 etc., not only those associated with the extractor which has been described, but also the similar controls of the other extractors, are controlled by the operation of cams on the cam shaft 25, which is driven at the proper ratio by the main 60 shaft 16. This control operation is shown diagrammatically in Fig. 5, where electrically operated valve 27 is controlled by the making and breaking of contacts 26 upon rotation of the cam shaft. The speed at which the cam shaft is 65 driven and the position of the various contacts for operating the electrically controlled mechanisms are so determined that the various operations necessary for the completion of the entire cycle of extraction follow each other in the proper sequence, as will be described below.

The operation in each extractor is very simple. The steam, dehydrating vapors, or solvent, as the case may be, is admitted into the extractor 70 after the car, loaded with chipped wood, is in place therein, through pipes 5, so incidentally

serving to keep the gears 13 well cleaned, and passes up through the chips through the perforations 10 in the cars. The vapors or solvent then passes out through pipe 7 and on to condensers, separators or evaporators, as the case may be. 5

Referring to Fig. 1, it will be seen that two extractors, A and B, are used for the steam distillation of turpentine from the fresh wood. In these extractors, live steam is admitted through valves V-11 and V-12 and passes out together 10 with the turpentine vapors through valves VV-11 and VV-12, passing normally through the heat exchangers HE-2, HE-3, etc., into the condenser C-1, and from there to the separator S-1 in which the turpentine is separated from the condensed water. In extractors C and D, which are used for dehydrating, the dehydrating vapor, which may be solvent vapors, as, for example, gasoline vapor, or furnace gas, passes into the extractors through valves V-9 and V-10 15 and out through valves VV-9 and VV-10 to the condenser C-2 and from there to the separator S-2. A pump P-1 is used to maintain a vacuum in extractors C and D.

Into extractors E to K, inclusive, which are used for rosin extraction of the dehydrated wood, the liquid solvent, for example, gasoline, is passed countercurrently; thus into extractor K through valve V-3, out through valve VV-3 through strainer ST-2 and heat exchanger HE-2 into 20 extractor J through valve V-4; thence through strainers and heat exchangers into extractors H, G, F and E in sequence, out of extractor E through valve VV-8 into evaporator E-1, from which the solvent vapors pass to condenser C-3, 25 separator S-3, and from there, by means of pump P-2, through heat exchanger HE-1 and back into extractor K through valve V-3. Any fresh solvent which may be required is pumped from the solvent supply by means of pump P-4 30 through heat exchanger HE-1.

Extractors L and M are used for the recovery of solvent by steam distillation. Into these extractors steam is passed through valves V-1 and V-2 and out through valves VV-1 and VV-2. 35 The steam, together with the solvent vapors, passing out of the extractors, goes through heat exchanger HE-1 and from there into condenser C-4 and separator S-4, from which the solvent is returned to the system through pump P-3. 40

The operation of the apparatus as a whole involving, as it does, the transfer of each car from one extractor to the next in series after completion of the operation in the first extractor 45 may best be described starting with the entire apparatus full of cars. That is to say, with reference to Fig. 1, there are 12 cars in the extractors A to M, inclusive, each car undergoing the treatment peculiar to the extractor in which it is. 50

Assume that one step of the cycle has been 60 completed and it is necessary to move ahead to the next step of the cycle.

As it takes considerable time to change all of the cylinders, it will be necessary to change them progressively while all other operations are still 65 being carried on.

Assume that the process is complete in cylinder M. Valves V-1 and VV-1 will be closed and vent valve VV-1A opened, permitting pressure to gradually decrease to atmospheric pressure. 70 Valve VV-1A will then be closed and valve VM opened.

The car containing the material processed will then be withdrawn from cylinder M. Valve VM will then be closed. Valve V-1 will then be 75

opened, admitting steam into cylinder M in order to bring the pressure up to the same condition as now exists in cylinder L. Valve VL will then be opened and the car of material in process in cylinder L will be passed into cylinder M.

5 Valve VL will then be closed and valve VV-1 opened, allowing steam to pass out of cylinder M.

Valves V-2 and VV-2 will be closed, shutting the steam off of cylinder L. Valve VV-2A will 10 be opened until the pressure is reduced to atmospheric in cylinder L. Valve V-31 will then be opened, admitting solvent into cylinder L until the cylinder is full, which will be indicated at the outlet of the vent line. Valve VV-2A will 15 then be closed.

When cylinder L is full of solvent, it will be at the same pressure as cylinder K, at which time valve VK will be opened and the car of material in process passed from cylinder K into cylinder L, 20 after which valve VK is closed.

Steam will then be passed into the top of cylinder L by opening valve VV-2 and closing valve VBP-1, and the solvent in cylinder L forced out through the bottom through valve V-31 into 25 cylinder K and so into the system.

When cylinder L is empty of solvent, it will be indicated by steam appearing at sample line SL.

Valve V-31 will then be closed and valve VBP-1 opened. Valve V-2 is then opened, admitting steam to the bottom of the cylinder, which will drive out the residual solvent in the material to be processed, through valve VV-2, through the heat exchanger, and thence through the condenser C-4, in the same manner as the process which 35 has already taken place and is taking place in cylinder M.

Cylinder K now having no car therein, a car of material in process can pass from J to K by opening valve VJ, and, when the car has passed, closing 40 VJ.

Another car can pass from cylinder H to cylinder J by opening valve VH, passing car and closing VH.

Another car can pass from cylinder G to cylinder H by opening valve VH, passing car and closing VG.

Another car can pass from cylinder F to cylinder G by opening valve VF, passing car and closing VF.

50 Similarly, a car can pass from cylinder E to cylinder F by opening valve VE, passing car and closing VE.

Each time after car has passed from one cylinder to another, the valve that was open to allow 55 the passing of the car is again closed.

During all of the previous operations, cars of material to be processed have been dehydrated in cylinders C and D.

Now D has been completely dehydrated ready 60 for subsequent operation in cylinder E.

In order to move car in process from cylinder D containing vapors into cylinder E containing some liquid solvent, valves V-9 and VV-9 are first closed on cylinder D and valve V-93 is opened

65 to equalize pressures in cylinders E and D by permitting solvent to flow from E to D. The valve VD between cylinders E and D is then opened and the car in cylinder D moved to cylinder E, after which valves VD and V-93 are closed and the process of solvent extraction is continued in cylinder E.

70 We now have cylinder D partly full of liquid solvent. This may be removed by leaving valve VV-9 closed and applying vapor pressure to cylinder D through valve V-91 from pump VP

and discharging the solvent remaining in cylinder D out of the bottom valve V-92 into the piping leading to the evaporator, thus leaving cylinder D empty. When the liquid has been removed, valve V-92 is closed, as is also V-91. Valve 5 VV-9 is then opened, allowing the pressure to be reduced in cylinder D by means of vacuum pump P-1, bringing it to the same pressure as cylinder C.

The car of material in process in cylinder C can 10 now be moved to cylinder D by opening valve VC, after which VC is closed. Later valve V-9 is opened to continue the dehydration.

Valve VV-10 on cylinder C is then closed; also, valve V-10 if vapors have been used for dehydra- 15 tion.

In order to move car of material to be processed from cylinder B to cylinder C, valves V-11 and VV-11 on cylinder B will be closed, and vent valve VV-11A opened until the pressure has been 20 reduced to atmospheric. Valve V-101 is then opened to equalize the pressure in the two cylinders B and C. Valves VV-11A and V-101 are then closed, and valve VB, between cylinders C and B, is opened, and the car is allowed to pass 25 from cylinder B into cylinder C, after which valve VB is closed.

Valve VV-10 on cylinder C is then opened and the process of dehydration continued, and later valve V-10 is opened to continued dehydration 30 with vapors.

Valve VV-11 and valve V-11 being closed, valve V-11 is then opened to bring the pressure up in cylinder B to that in cylinder A, and valve VA between cylinders A and B is then opened 35 and the car is allowed to pass from cylinder A to cylinder B, after which valve VA is closed. Valve VV-11 is then opened and the material in cylinder B is processed.

Valves V-12 and VV-12 on cylinder A are 40 now closed and vent valve VV-12A opened, allowing the pressure to be reduced in cylinder A to atmospheric. Valve VV-12A is closed. Valve VA-1 is then opened and a new carload of material to be processed enters cylinder A, after 45 which VA-1 is closed. Valve V-12 is then opened, admitting steam into cylinder A. Valve VV-12 is also opened, and the process of the extraction continued.

The sequence of operation of the electrically 50 operated controls in the cycle described is diagrammatically shown in Fig. 2.

The number of cylinders in each particular operation is so arranged that when the time cycle is completed on cylinder A, cylinder M will 55 be ready for its next cycle of operation and the car can be removed from M in the manner described above and the whole process of moving a car from one cylinder section to another repeated, and so on indefinitely.

60 Any number of cylinders can be used in any particular part of the operation, all depending upon the time necessary for the operation to be performed.

The size of the cylinders, valves, interconnect- 65 ing piping, etc. can be made of any convenient size for a definite amount of material to be processed in a given time.

Returning now to the car which was removed from extractor M at the beginning of the cycle 70 of operations just described, this car will be moved onto a transfer table, carried across to a track extending over a dump, moved into position over the dump, inverted by an unloader of the usual type and the extracted chips there- 75

in contained discharged into a bin from which they may be fed into the furnaces of the plant. The car is then sent to a second transfer table on which it is shunted across to the track leading into extractor A and placed under hoppers from which the fresh wood supply, in the form of chips, is discharged into the car. The car is then ready to be introduced into extractor A at the proper point in the cycle.

10 As will be seen, the time during which any car may remain in any one of the extractors is limited, by the continuous nature of the process, to the same period, no matter what process may be carried on in the extractor. Hence, 15 necessary variations in the periods of time to which the chips must be subjected in the different operations is permitted by increasing or decreasing the number of extractors in the group of extractors in which the same operation takes 20 place. Thus, in the process outlined, two extractors each were used for turpentine distillation, dehydration and solvent recovery, respectively; while six extractors were used for rosin extraction. By changing the number of extractors in these groups, the entire apparatus and method may be made exceedingly flexible, so that any desired processing treatment can be given.

What I claim and desire to protect by Letters 30 Patent is:

1. Apparatus for the continuous extraction of resinous wood comprising a horizontal chamber of great length in relation to its cross-sectional area, means for dividing said chamber into a 35 plurality of isolated small chambers, means for introducing and removing fluid agents into and from each small chamber so formed, means for passing resinous wood through each of said small chambers in sequence, and master-control 40 means adapted to effect automatically in predetermined sequence and at predetermined intervals the operation of said above named means.

2. Apparatus for the continuous extraction of resinous wood comprising a horizontal chamber 45 of great length in relation to its cross-sectional area, means for dividing said chamber into a plurality of isolated small chambers, means for introducing and removing fluid agents into and from each small chamber so formed, rails laid 50 the length of said large chamber, cars travelling on said rails and adapted to carry resinous wood, said cars being perforated for the passage of fluids therethrough, means for moving said cars through each of said small chambers in sequence, 55 and master-control means adapted to effect automatically in predetermined sequence and at predetermined intervals the operation of said above named means.

3. Apparatus for the continuous extraction of 60 resinous wood comprising a horizontal chamber of great length in relation to its cross-sectional area, gate valves for dividing said chamber into a plurality of isolated small chambers, means for

operating said gate valves, means for equalizing the pressure conditions in adjacent small chambers, means for introducing and removing fluid agents into and from each small chamber, rails laid the length of said large chamber, cars 5 travelling on said rails and adapted to carry resinous wood, said cars being perforated for the passage of fluids therethrough, and means for moving said cars through each of said small chambers in sequence. 10

4. Apparatus for the continuous extraction of resinous wood comprising a horizontal chamber of great length in relation to its cross-sectional area, gate valves for dividing said chamber into a 15 plurality of isolated small chambers, means for operating said gate valves, means for equalizing the pressure conditions in adjacent small chambers, means for introducing and removing fluid agents into and from each small chamber, rails laid the length of said large chamber, cars 20 travelling on said rails and adapted to carry resinous wood, said cars being perforated for the passage of fluids therethrough, means for moving said cars through each of said small chambers in sequence, and master-control means 25 adapted to effect automatically in predetermined sequence and at predetermined intervals the operation of said above named means.

5. Apparatus for the continuous extraction of resinous wood comprising a horizontal chamber 30 of great length in relation to its cross-sectional area, means for dividing said chamber into a plurality of isolated small chambers, means for introducing and removing fluid agents into and from each small chamber so formed, rails laid 35 the length of said large chamber, cars travelling on said rails and adapted to carry resinous wood, said cars being perforated for the passage of fluids therethrough, means for moving said cars through each of said small chambers in sequence, 40 and means positioned between said cars and the walls of said chambers and adapted to prevent any fluid introduced into said chambers from passing from inlet to outlet thereof between the cars and chamber walls. 45

6. Apparatus for the continuous extraction of resinous wood comprising a horizontal chamber of great length in relation to its cross-sectional area, means for dividing said chamber into a plurality of isolated small chambers, means for 50 introducing and removing fluid agents into and from each small chamber so formed, rails laid the length of said large chamber, cars travelling on said rails and adapted to carry resinous wood, said cars being perforated for the passage of 55 fluids therethrough, a gear rack carried by each of said cars, pinions positioned in each of said small chambers and engaging said gear racks, and driving means for said pinions, whereby the said cars may be moved from chamber to chamber.

GEORGE E. RAMER.
